(57) **CLAIM**

The ornamental design for an electric cleaning brush, as shown and described.

DESCRIPTION

FIG. 1 is a front, top and right side perspective view of an electric cleaning brush showing my new design;
FIG. 2 is a rear, bottom and left side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the selected portion 9 in FIG. 1.

The broken lines shown in the drawings depict portions of the electric cleaning brush that form no part of the claimed design.
